US00D768888S

(12) **United States Design Patent** (10) **Patent No.:** **US D768,888 S**
Tan et al. (45) **Date of Patent:** **** Oct. 11, 2016**

(54) **LED LIGHTING MODULE**

(71) Applicant: **OSRAM GmbH**, Munich (DE)

(72) Inventors: **Jie Tan**, Shenzhen (CN); **HongWei Zhang**, Shenzhen (CN)

(73) Assignee: **OSRAM GMBH**, Munich (DE)

(**) Term: **15 Years**

(21) Appl. No.: **29/548,052**

(22) Filed: **Dec. 10, 2015**

(30) **Foreign Application Priority Data**

Jun. 11, 2015 (EM) 002717462

(51) **LOC (10) Cl.** **26-04**

(52) **U.S. Cl.**

USPC **D26/1**; D13/180

(58) **Field of Classification Search**

USPC D13/180; D26/1-4, 24, 120

CPC F21K 9/00; F21K 9/13; F21S 4/20;

F21V 5/007; F21V 5/02; F21V 5/04; F21V

19/003; F21V 31/04; F21V 23/005

See application file for complete search history.

(57) **CLAIM**

The ornamental design for an LED lighting module, as shown and described.

DESCRIPTION

FIG. 1 is a perspective view of the lighting module;

FIG. 2 is a front view of the lighting module;

FIG. 3 is a back view of the lighting module;

FIG. 4 is a right side view of the lighting module;

FIG. 5 is a left side view of the lighting module; and,

FIG. 6 is a top view of the lighting module.

1 Claim, 6 Drawing Sheets
